ATTORNEY

UNITED STATES PATENT OFFICE

EDWIN BURT, OF CANUTILLO, TEXAS

FILTER

Application filed December 10, 1928. Serial No. 225,035.

The invention relates to improvements in filters such as disclosed in my prior Patent, No. 931,267, dated August 17, 1909, and has for its primary object the provision of improved means for effecting discharge of the contents of the filter chamber.

Another object of the invention is the provision of an arrangement of this character by means of which the discharge of the chamber may be quickly and conveniently effected.

Another object of the invention is the provision of an arrangement of this character entirely mounted on and contained in the filter chamber.

Other objects will appear hereinafter.

The invention consists in the combinations and arrangement of parts hereinafter described and claimed.

The invention will be best understood by reference to the accompanying drawings forming a part of this specification and in which—

Fig. 1 is a partial vertical section taken through the discharge end of the filter chamber and showing discharging means embodying the invention;

Fig. 2, a detail view showing a connecting collar employed in the construction; and

Fig. 3, a section taken substantially on the line 3—3 of Fig. 1.

The preferred form of construction, as illustrated in the drawings, comprises a suitable revolving filter chamber 4 having a removable discharge end 5 bolted thereto as indicated.

The discharge end 5 is provided with a plurality of discharge openings arranged immediately adjacent to internal periphery of the chamber 4. Each of said openings is guarded and protected by means of a nipple 6, which may be of special non-corrosive metal, secured in place as shown. At its inner end, each nipple 6 is provided with a conical valve surface, effecting a tight seal with the inner portion of the opening and also projecting into the interior of the chamber to constitute a valve or closure seat 7. Each of said openings is closed by means of a valve or closure head 8 rigidly secured to the inner end of an operating stem 9 projecting through the corresponding opening

and rigidly secured at its outer end to a corresponding lever 10. The levers 10 are arranged in radiating positions, being fulcrumed at 11 between suitable ears 12 formed on the outer side of the chamber end 5. At its inner end, each of the levers 10 is provided with a slot 13 engaging a corresponding pin 14 between parallel ears 15 on the inner face of a collar 16. The collar 16 is split, as indicated, into two halves secured together by bolts 17 and is provided with an internal annular groove engaging an annular flange 18 on the inner end of a nut sleeve 19. The nut sleeve 19 is threaded on a central post 20 and provided with a hand wheel 21 for manipulation of the same. At its outer end, the post 20 is provided with a stop collar 22 held in place by a nut 23 and is enclosed and protected by a guard cap 24.

By this arrangement, the valves or closure heads 8 may be simultaneously operated by manipulating the hand wheel 21 to open or close the discharge openings through the chamber end 5, as will be readily understood. This constitutes a simple and efficient arrangement for the purpose, mounted entirely upon the filter chamber and requiring no additional support or mechanism.

A relief valve 25 is also provided on the end 5 to permit of relief of internal pressure in the filter chamber, thus facilitating opening of the valves 8. A suitable manhole and cover 26 is also provided for giving access to the interior of the filter chamber.

While the preferred form of construction for carrying the invention into effect has been illustrated and described, this is capable of variation and modification without departing from the spirit of the invention. It is, therefore, not desired to limit the patent to the precise details disclosed but to include therein also such variations and modifications as fall within the scope of the appended claims.

I claim:

1. In a filter of the type specified, the combination of a hollow casing, means for rotatably mounting said casing, a fixed head for closing the discharge end of said casing provided with a discharge opening, a closure for

said opening, and means mounted on the discharge end of the filter casing for supporting and operating said closure to close, open and position the same, said means forming a 5 constituent part of the filter.

2. A filter as specified in claim 1, in which the closure for the discharge opening opens inwardly.

3. In a filter of the type specified, the combination of a hollow casing, means for rotatably mounting said casing, a fixed head 10 for closing the discharge end of said casing provided with a plurality of spaced discharge openings, arranged adjacent its periphery, 15 an individual closure for each discharge opening, and means mounted on the discharge end of the filter casing for supporting and operating said closures to simultaneously close, open and position the same, 20 respectively.

4. A filter as specified in claim 1, which comprises a lever pivotally mounted on the discharge end of the filter casing to which the closure is secured, a threaded post secured 25 in the discharge end of said filter casing, a nut having threaded engagement with said post, and operative connection between said nut and lever.

5. A filter as specified in claim 1, which 30 comprises a lever mounted on the discharge end of the filter casing, a stem rigidly secured thereto, which extends through the discharge opening into said filter casing, to the outer end of which said closure is rigidly 35 secured, a threaded post secured in the end of said filter casing, a nut having threaded engagement with said post, and operative connection between said nut and lever.

6. A filter as specified in claim 3, which 40 comprises a plurality of levers pivotally mounted on the discharge end of the filter casing, a stem rigidly secured in each of said levers, to the outer ends of which, respectively, one of said closures is rigidly secured, 45 a threaded post secured in the end of said filter casing, a nut having threaded engagement with said post, and operative connection between said nut and levers.

7. A filter as specified in claim 3, which 50 comprises a plurality of levers pivotally mounted on the end of said filter casing, outside thereof, a stem rigidly secured in each of said levers which extends through a discharge opening into said receptacle, to the 55 outer end of which the closure for the opening through which said stems extend, respectively, is secured, a threaded post secured in the end of said receptacle, a nut which has threaded engagement with said post, and operative connection between said nut and levers.

In witness that I claim the foregoing as my invention, I affix my signature this 30 day of November, 1928.
